UNITED STATES PATENT OFFICE.

WILLIAM M. HANLINE, OF PHILADELPHIA, PENNSYLVANIA, ASSIGNOR TO
ALEXANDER M. HANLINE, OF BALTIMORE, MARYLAND.

DESIGN FOR A NAIL OR SPIKE.

SPECIFICATION forming part of Design No. 28,287, dated February 15, 1898.

Application filed November 20, 1897. Serial No. 659,335. Term of patent 14 years.

To all whom it may concern:

Be it known that I, WILLIAM M. HANLINE, a citizen of the United States, residing at Philadelphia, in the county of Philadelphia and State of Pennsylvania, have invented or 5 produced a new and original Design for a Nail or Spike, of which the following is a specification.

This design has for its object to provide a 10 novel nail or spike which presents an ornamental and characteristic appearance to the eye.

The leading feature of the design consists in a nail or spike cylindrical in cross-section, 15 gradually tapering from top to bottom, and having along its shank a plurality of lateral spurs which alternately project from opposite sides thereof and are formed with beveled sides to provide their outer portions with 20 knife-edges, the upper or outer ends of the spurs being shouldered and their lower portions vanishing gradually into the shank to produce a neat symmetrical form or shape.

The design is illustrated by the accompanying drawings, in which—

Figure 1 is a side elevation of my new design for a nail or spike. Fig. 2 is a transverse sectional view taken on the line 2 2, Fig. 1, to more clearly illustrate the beveled construction of the spurs by which they are brought 30 to knife-edges at their outer portions.

In the accompanying drawings, the numeral 1 indicates the nail or spike, the shank of which, as shown, is circular in cross-section and gradually tapering from top to bottom, and at its lower end is more or less abruptly tapered to a point 2. The shank is formed integral along its length with a plurality of laterally-projecting spurs 3, which alternately extend from opposite sides thereof. The upper or outer ends of the spurs are shouldered, as at 4, and, as shown, these shoulders are beveled downward. The lower portions of the spurs gradually vanish into the body of the shank, as at 5. The sides of 45 each spur are beveled, as at 6, to provide their outer portions with knife-edges, as at 7.

The design provides a novel nail or spike which is ornamental and symmetrical and presents a peculiar and characteristic appearance to the eye.

What I claim is—

The design for a nail or spike, substantially as shown and described.

In testimony whereof I have hereunto set 55 my hand in presence of two subscribing witnesses.

WILLIAM M. HANLINE.
